UNITED STATES PATENT OFFICE.

JOHN ILLINGWORTH, OF NEWARK, NEW JERSEY.

MOLD FOR CASTING INGOTS OF ALTERNATE LAYERS OF METAL.

SPECIFICATION forming part of Letters Patent No. 320,560, dated June 23, 1885.

Application filed March 17, 1884. (No model.)

To all whom it may concern:

Be it known that I, JOHN ILLINGWORTH, a citizen of the United States, residing at Newark, in the county of Essex and State of New Jersey, have invented certain new and useful Improvements in Molds for Casting Ingots of Alternating Layers of Metal; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to facilitate the process of producing ingots of alternating layers of hard and soft steel or other metals, and to reduce the cost of the same.

It consists in the arrangements and combinations of parts substantially as will be hereinafter set forth, and finally be embodied in the clauses of the claim.

Referring to the accompanying drawings, embodied in two sheets, in which similar letters of reference indicate like parts in each of the several figures, Figure 1 is a side elevation of the improved device, partially in section, to show the internal construction thereof. Fig. 2 is a plan of the same, showing the center formed in elevation, the base partly in section, the left mold in elevation with its cover on, and the right mold in section with its cover off, and with the metal plates and plate-holders in section. Fig. 3 is a vertical section taken through line *x*, and Fig. 4 is a detail plan of the foundation-piece.

In carrying out the invention I form the mold of several detachable sections, preferably of cast-iron, of which *a* is the base, having therein grooves or passages *b*, leading from a central funnel, *c*, to one or more upright ingot-molds or plate-receptacles. Said grooves are lined and covered with suitable fire-bricks, *b' b''*, the covering-brick being removable.

The ingot-molds or plate-receptacles *d* are formed of foundation-pieces *e* and hollow uprights *h'*. The foundation-pieces *e* are provided with inclined inner sides, *f*, and wedge-shaped projections *g*, adapted to separate the lower extremities of the steel plates *h* when

the latter are dropped into the said molds, and to hold them at suitable distances apart and from the side walls of the receptacles, as will be understood upon reference to Fig. 1. 55 Upon the foundation-pieces *e* are placed the hollow uprights or molds *h'*, which approximate the length of the plates *h*.

In casting the ingots, which are to be of alternating layers of differing metal, I place 60 the metallic plates or bars *h* longitudinally in the vertical receptacles, the lower ends being separated in the lowering process by the wedge-shaped projections *g*, and brought to a proper distance from the wall of the receptacle by 65 the inclined side surfaces, *f*. Said lower extremities rest on suitable ledges or shoulders, *j*, and are thereby held up into proper relative position in the receptacle to allow the molten metal coming up through the passages 70 *b* to pass around on all sides of the plate or plates *h*. The upper extremities of the said plates are correspondingly held apart and from the walls of the receptacle by notched cross-strips *l* and side wedges, *m*, as shown in 75 Fig. 3, or by any other suitable means.

The receptacles are provided with a cover, *n*, to close the mouth thereof. Said covers are supported by the notched strips *l* and *m*, which hold the covers, and the plates *h* fit loosely, so as to allow the plate-chambers to be 80 vented.

The funnel *c* may be lined with tubular tile or fire-brick *s*.

In operation the plates *h* are heated, so as 85 not to chill the molten metal, and placed in position in the receptacle, after which the molten metal is poured through the funnel *c* and passes through the passage *b*, entering the receptacles *a*, and filling the spaces around and 90 between the plates *h*, the plates and cast metal forming, when cool, an ingot of alternating layers.

I do not wish to be understood as limiting myself to the exact construction and arrangement of parts shown, as numerous changes may be made without departing from the spirit of the invention. 95

When the metal is hardened, the portion *d* is drawn off by a suitable crane or other tackle, handles or means *p* being provided to receive said tackle.

Having thus described the invention, what I claim as new is—

1. In a mold for casting ingots of alternating layers of metal, a plate-receptacle having 5 inclines *f* and wedge-shaped guides *g*, substantially as and for the purposes set forth.
2. In combination, the base *a*, the funnel, and one or more plate-receptacles, each consisting of a foundation-piece provided with 10 means for spacing and supporting one or more metal plates and a hollow upright, *h*, said base having therein passages *b*, leading from said funnel to said receptacle or receptacles, substantially as and for the purposes set forth.
3. The combination of a funnel, one or more 15 ingot-molds, one or more metal plates in each mold, and a passage extending from the funnel to each mold or plate-receptacle, and to a position under the plate or plates therein, whereby the metal passes beneath and up- 20

wardly on both sides of the plate or plates, as and for the purposes set forth.

4. In a mold for casting ingots of alternating layers of metal, a plate-receptacle having ledges *j*, inclines *f*, and guides *g*, arranged and 25 operating substantially as and for the purposes set forth.

5. In combination, the base having passages therein, the funnel, the uprights *h*, and foundation-pieces *e*, provided with wedge-shaped 30 projections, all said parts being arranged and operating substantially as set forth.

In testimony that I claim the foregoing I have hereunto set my hand this 12th day of March, 1884.

JOHN ILLINGWORTH.
